DESIGN FOR A GAME BOARD

Walter J. Hohn, Detroit, Mich.

Application April 27, 1939, Serial No. 84,601

Term of patent 7 years

To all whom it may concern:

Be it known that I, Walter J. Hohn, a citizen of the United States, residing at Detroit, in the county of Wayne and State of Michigan, have invented a new, original, and ornamental Design for a Game Board, of which the following is a specification, reference being had to the accompanying drawing, forming part thereof.

The figure is a plan view of a game board showing my new design.

The game board is of ordinary or conventional thickness and the small circles represent holes through the board, the surface of which is lined and featured as shown, portions being lined to indicate contrasting color.

I claim:

The ornamental design for a game board, as shown and described.

WALTER J. HOHN.
